SHRIMP CLEANER HANDLE

Thomas S. Gorton, Jr., 993 Memorial Drive,
Cambridge, Mass.

Filed June 8, 1959, Ser. No. 56,272

Term of patent 14 years

(Cl. D44—29)

FIG. 1

FIG. 2

FIG. 3

FIG. 4

FIG. 5

FIG. 1 is a side elevational view of a shrimp cleaner handle showing my new design;

FIG. 2 is a top view thereof;

FIG. 3 is a bottom view thereof;

FIG. 4 is a cross sectional view taken on the line 4—4 of FIG. 1; and

FIG. 5 is a cross sectional view taken on the line 5—5 of FIG. 1.

I claim:

The ornamental design for a shrimp cleaner handle, as shown.
